UNITED STATES PATENT OFFICE

125,083

DESIGN FOR A SLIDE FOR OVERALL STRAPS
OR THE LIKE

William E. Dickson, St. Louis, Mo., assignor to
The Patent Button Company, Waterbury, Conn.,
a corporation of Connecticut

Application October 2, 1940, Serial No. 95,593

Term of patent 14 years

To all whom it may concern:

Be it known that I, William E. Dickson, a citizen of the United States, residing at St. Louis, in the State of Missouri, have invented a new, original, and ornamental Design for Slide for Overall Straps, or the like, of which the following is a specification, reference being had to the accompanying drawing, forming part thereof, in which:

Fig. 1 is an enlarged top plan view of a slide for overall straps or the like, showing my new design;

Fig. 2 is a bottom view thereof;

Fig. 3 is an end view thereof;

Fig. 4 is a transverse sectional view on the line 4—4 of Fig. 1;

Fig. 5 is a sectional view on the line 5—5 of Fig. 1; and

Fig. 6 is a longitudinal sectional view on the line 6—6 of Fig. 1.

I claim:

The ornamental design for a slide for overall straps or the like, as shown.

WILLIAM E. DICKSON.
